UNITED STATES PATENT OFFICE.

FOSTER F. HILLIX, OF CLEVELAND, OHIO, ASSIGNOR TO WHITE SEWING MACHINE COMPANY, OF CLEVELAND, OHIO, A CORPORATION OF OHIO.

SEWING-MACHINE-MOTOR CONTROL.

Application filed March 30, 1922. Serial No. 548,243.

To all whom it may concern:

Be it known that I, FOSTER F. HILLIX, a citizen of the United States, residing at Cleveland, in the county of Cuyahoga and 5 State of Ohio, have invented a certain new and useful Improvement in Sewing-Machine-Motor Controls, of which the following is a full, clear, and exact description.

This invention relates to a sewing machine 10 motor control and is designed as an improvement over the construction constituting the subject matter of my prior application Serial No. 500,700, filed September 14, 1921.

In my prior application above referred to, 15 I have shown a control for a motor driven sewing machine which includes a depending actuating member having a suitable connection with the motor controlling rheostat. This member is designed to extend down 20 close to the floor and is adapted to be laterally displaced primarily by a lateral movement of the foot when resting on the floor, the controlling or actuating member having a universal mounting which enables the oper-

25 ator to control the motor by displacing the member from normal position laterally in any direction. Furthermore the actuating or controlling member can be swung to a variety of positions without disturbing its 30 operative connection with the motor rheostat, including a position wherein it serves as a foot control; also a position where it serves as a knee or leg control and if desired, a position wherein the actuating member oc- 35 cupies a concealed position substantially within the confines of the walls of the cabinet of the machine. With this construction the operator may hold the lever displaced so as to run the machine at the desired speed with 40 her foot in comfortable position on the floor and resting in a natural position, and inasmuch as the actuating member has practically a universal motion, if the operator is accustomed to a knee or leg control or should 45 perchance prefer a knee or leg control, the actuating member may be swung to a position to permit this method of control.

In the construction shown in my prior application the actuating member is connected to one of two co-axial swiveled cup- 50 like members, one of which is connected to the rheostat controlling member, these swivel members permitting the actuating member to be swung to any desired position 55 to suit the kind of control that the operator

may desire, and additionally one of these swivel members is capable of a universal rocking motion on the other, which rocking motion causes the rheostat arm to be shifted, and inasmuch as the rocking motion is universal, it can be produced by moving the actuating member in any lateral direction. 60

The subject matter of the present invention is a sewing machine control constructed along the lines of that constituting the subject matter of my prior application, and the principal object of the present invention is to provide certain structural features and arrangements which improve the action and efficiency of the controlling mechanism, increase its utility and durability, and render it more desirable from a manufacturing stand-point. 65

The invention may be briefly summarized as consisting in certain novel details of construction and combinations and arrangements of parts which will be described in the specification and set forth in the appended claims. 70

In the accompanying sheets of drawings 80 wherein I have shown the preferred embodiment of the invention, Fig. 1 is a view looking toward the front of the sewing machine equipped with my improved motor control, parts being broken away; Fig. 2 is a perspective view of the actuating member and its mounting detached from the machine; Fig. 3 is a sectional view through the same showing some additional control features; Fig. 4 is an enlarged sectional view through a cabinet showing the main parts of the control; Fig. 5 is a face view of the control mechanism illustrating the manner in which the actuating or controlling member can be shifted to various operative positions and also 85 illustrating the manner in which it can be displaced laterally when in any operative position to control the rheostat; Fig. 6 is a face view of the base plate of the control mechanism; and Fig. 7 is a view looking 90 toward the right of Fig. 6.

Referring now to the drawings, 10 represents a conventional form of sewing machine cabinet or stand and 11 represents the sewing machine head. The machine here shown 105 may be of the drop head type, in which event the head will be mounted on a swinging platform so that it can be lowered into the cabinet.

The motor for driving the machine may 110

be mounted at any suitable point such as on the platform carrying the head, or on the arm of the head, and in this instance for convenience it is shown as mounted on the 5 rear side of the arm of the head, the motor being indicated by dotted lines in Fig. 1 and designated by the reference character 12. The drive between the motor and operating shaft of the sewing machine may 10 assume any desired form, as for example, the friction drive, in which event the motor will have a small friction drive wheel 13 held in frictional engagement with the hand wheel 14 of the head.

15 The rheostat for controlling the operating motor 12 is shown at 15, but as the details of this rheostat constitute no part of the present invention the rheostat is shown in outline only, and it will be sufficient to 20 state that it includes a movable arm, which when shifted in one direction starts the motor and gradually cuts out resistance so as to increase its speed, and when moved in the reverse direction toward off position, 25 usually by a spring contained in the rheostat, it cuts in resistance so as to decrease the speed of the motor and finally opens the motor circuit. In the embodiment shown, the movable arm of the rheostat is 30 indicated at 16.

The rheostat may be mounted on any suitable part of the sewing machine, either in a stationary position or if desired it may be mounted on the bottom of the swinging 35 platform carrying the head 11 as shown and described in my prior application.

The motor control mechanism including the rheostat, the actuating member already referred to, and the mechanism connecting 40 it to the rheostat operating part are supported on the inside of the cabinet at or adjacent the corner formed by the back wall and the right hand end wall.

Taking up now the details of this mechanism and starting with the part which directly actuates the rheostat, it will be observed that the rheostat arm 16 which in this instance is designed to be moved vertically, is engaged by a lever 17, mounted on 45 a bracket 18 attached to the end wall of the cabinet adjacent the corner. When the lever 17 is pulled downward it lowers the rheostat arm 16 so as to operate the motor, and when the lever 17 is lifted, the rheostat 50 arm 16 may rise to slow down and finally open the circuit of the motor. In this instance the lever 17 is shifted by a link or rod 19 which is connected to a triangularly shaped lever 20 which is pivoted at 21 to 55 an ear or extension of a stationary base plate 22 which is supported in inclined position as shown in Fig. 1, in the angle formed by the back and right hand end walls of the cabinet, this plate being inclined as shown 60 in the several figures of the drawing. The

plate is attached to the cabinet by screws passing through ears in the form of extensions of the plate 22.

On the front side of this inclined plate 22 are two co-axial cup-shaped members 70 23 and 24, in the form of truncated cones, these two members being nested as shown, and the inner member 23 engaging in a manner hereinafter described, the base plate 22. The two cup-shaped members 75 23 and 24 are held in nested position but so that the outer member 24 may turn on the inner member 23 by the equivalent of an axially disposed central hollow rivet 25, and extending through this hollow rivet is 80 a short rod 26 having a shoulder in the form of a cotter pin 27 or equivalent means at its outer lower end and engaging the outer face of the hollow rivet, and at its upper rear end being connected to the triangular shaped lever 20 as clearly illustrated 85 in Fig. 3.

A spring 27 is connected to this lever 20 and to a stationary point, in this instance to the bracket 18 above it, the function of 90 this spring being to hold the parts in their normal position with the inner cup-shaped member bearing firmly against the base plate, and with the triangular shaped lever 20 and the upper lever 17 in elevated positions. It is to be noted that the rod 26 passes loosely through a centrally disposed hole in the base plate so as to allow a certain rocking movement of the cup-shaped members 23 and 24 on the base plate, which 100 rocking movement is universal, as will be pointed out subsequently.

The rheostat actuating member which is operated by the foot or knee of the operator, is shown at 28, this member being preferably 105 in the form of a light tube which as in my prior application extends down close to the floor if the member is to be actuated by the foot of the operator, but is capable of being turned to various other positions, and, in fact, may be revolved so as to describe a conical surface whose axis corresponds to the axis of the cup-shaped members 23 and 24 when the former is bearing, 110 as it normally does, solidly against the base plate 22.

The actuating member 28 is preferably flared outwardly adjacent its upper end and is rigidly attached to the outer conical wall 115 of the cup-shaped member 24.

Inasmuch as the outer cup-shaped member 24 may be turned on the inner cup-shaped member 23, and since the actuating member is rigid with the outer member 24, it is obvious that the actuating member 28 120 may be placed in any one of its operative positions, and, in fact, may be revolved in the manner just stated, by turning the actuating member and the cup-shaped member 24 about the axis of the latter.

I prefer to provide in the wall of the inner cup-shaped member 23 a series of positioning openings, and to provide in the actuating member 28 a longitudinally movable 5 detent, here shown as a plunger 29, pressed upwardly by a spring 30 so that its reduced inner end will project through an opening in the outer cup-shaped member 24 in line with the tubular member 28, and into any 10 one of the positioning openings in the inner cup-shaped member 23, one of which openings I have shown in Fig. 3. Preferably the plunger or detent 29 is provided with a laterally projecting actuating portion 31 which 15 extends out through a slot in the tube 28 so that the plunger can be withdrawn so as to cause the upper end to be removed from engagement with any one of the positioning openings of the inner cup-shaped member 23.

I preferably provide three such openings in the member 23, one which will position the actuating member 28 so that it may be used as a foot control, in which event the 25 member 28 normally occupies a position substantially as shown in Fig. 1. This position is indicated in Fig. 5 by the reference character A. Other openings are provided in this member 23 so that the actuating 30 member may be swung upwardly and positioned alongside the end wall of the cabinet to the dotted line position which I have shown in Fig. 5, and designated B, and also to the position which I have shown by dotted lines and indicated by the reference character C, this being an elevated position inside the wall of the cabinet which is the inoperative concealed position. These positions correspond precisely to the three positions particularly pointed out in my prior 35 application.

A very important feature of the present invention is the manner in which the inner cup-shaped member 23 is designed to engage 45 the base plate 22 and to be rocked thereon, by lateral movement of the actuating member 28 in any of its operative positions. In this instance the base plate is provided opposite the inner edge or margin of the cup-shaped member 23 with an annular series of 50 perforations 32, and the member 23 is provided at its inner edge with an annular series of teeth 33 which are so spaced and positioned that they will normally fit into the 55 series of openings 32, that is to say, all the teeth will fit into the openings 32 when the actuating member 28 is in normal position, in which event the member 23 bears solidly against the base plate.

60 However, when the actuating member when in any operative position is moved laterally by the foot or knee of the operator to actuate the rheostat, both cup-shaped members rock with reference to the base plate, in 65 which event, part of the teeth 33 leave the

corresponding openings 32 in the manner illustrated in Fig. 2, while other teeth remain in engagement with the openings which normally receive them. In fact, with this construction the inner cup-shaped member may 70 have the equivalent of a rolling action and the actuating member has a universal movement when in any operative position which will admit of its being moved in any direction by the operator, but when the pressure 75 of the foot or knee is released, the parts are restored to their previous position with the teeth of member 23 again fitting into the openings of the base plate.

Whenever the actuating member is moved 80 laterally rocking the cup 23 so as to disengage part of its teeth from the openings 32 of the base plate the rod 26, lever 20, link or rod 19 and lever 17 are pulled downward so as to actuate the rheostat, and this takes 85 place as before stated, irrespective of the direction in which the rocking movement takes place.

It will be seen, therefore, that the principle of this control is identical with the control of my prior application, but that the details have been greatly improved, these 90 improvements eliminating loose play and providing a construction which is of great durability, as continuous testing equivalent 95 to years of normal use has proven, and providing also a construction which from a manufacturing standpoint as to low cost and ease of production is very desirable.

While I have shown the preferred embodiment of the invention, I do not desire to be confined to the exact details shown, but aim in my claims to cover all modifications which do not involve a departure from the spirit and scope of my invention.

Having described my invention, I claim:

1. The combination with a sewing machine having a motor and a controller therefor, of means for actuating the controller comprising a pair of nested members connected to the controller, an actuating member connected to one of said members, said nested members being capable of simultaneous rocking movement to admit of a substantially universal rocking movement to 115 be given to the actuating member.

2. The combination with a sewing machine having a driving motor and a controller therefor, of means for actuating the controller comprising a pair of nested members having a connection with the controller, and one provided with a depending actuating member and capable of rotation on the other, and both capable of a rocking movement.

3. The combination with a sewing machine having a driving motor and a controller therefor, of means for actuating the controller comprising a pair of nested members having a connection with the controller,

- 4 and one provided with a depending actuating member and capable of rotation on the other, and both capable of a rocking movement, the nested portions of said members being conical.
5. The combination with a sewing machine having a driving motor and a controller therefor, of means for actuating the controller comprising two adjacent members one capable of a tilting or rocking motion on the other, and one having teeth and the other openings which normally receive the teeth.
6. The combination with a sewing machine having a driving motor and a controller therefor, and means for actuating the controller comprising a stationary member and a universally tilttable member engaging the same, one having an annular series of openings and the other an annular series of teeth normally engaged in the openings.
7. The combination with a sewing machine having a driving motor and a controller therefor, and means for actuating the controller comprising two adjacent members one capable of a tilting or rocking motion on the other, and one having teeth and the other openings which normally receive the teeth, and a depending actuating member connected to the tilttable member.
8. The combination with a sewing machine having a driving motor and a controller therefor, of means for actuating the controller comprising one member rotatable on another and provided with a depending actuating part and also having an operative connection with the controller, said actuating member having a locking detent by which said first two members are held in predetermined position one with respect to the other.
9. In combination with a sewing machine having a driving member and a controller therefor, of means for actuating the motor comprising a pair of hollow tilttable members connected to the controller, one member being rotatable on the other and provided with a depending actuating handle and a detent movable lengthwise of the handle for releasing said two members so that they may be turned relatively and for locking them together.

In testimony whereof, I hereunto affix my signature.

FOSTER F. HILLIX.
